UNITED STATES PATENT OFFICE.

ALLA B. BICKHAM, OF LENOIR, LOUISIANA.

BABY HOME.

Application filed September 16, 1922. Serial No. 588,685.

To all whom it may concern:

Be it known that I, Mrs. ALLA B. BICKHAM, a citizen of the United States, residing at Lenoir, in the parish of De Soto and 5 State of Louisiana, have invented certain new and useful Improvements in a Baby Home, of which the following is a specification.

The present invention relates to a baby 10 home and has for its principal object to provide a vehicle containing all the necessary requisites for providing a comfortable living quarters for a baby.

Another object of the invention is to provide 15 a device of this nature which will be simple and efficient in construction, reliable in operation and well adapted to the purpose designed.

With the above and numerous other objects in view the invention consists of certain novel features of construction and the arrangement and combination of parts as will be hereinafter fully described and claimed.

25 In the drawing:—

Figure 1 is a side elevation of the vehicle embodying my invention,

Figure 2 is a longitudinal central section taken vertically therethrough,

30 Figure 3 is a rear elevation thereof showing the sections extended,

Figure 4 is a similar view showing the sections together,

35 Figure 5 is a section taken on the line 5—5 of Figure 1 looking in the direction of the arrows,

Figure 6 is a detailed vertical section taken through the rear portion of the device showing the table extended,

40 Figure 7 is a fragmentary transverse vertical section taken through the device,

Figure 8 is a fragmentary enlarged sectional view showing in detail certain important constructions, and

45 Figure 9 is a fragmentary sectional view taken vertically through the upper portion of one side of the device showing the operation of the cover.

Referring to the drawings in detail it will 50 be seen that the device is mounted on the wheels 1 which may be of any preferred construction and mounted in any suitable manner. Two of these wheels are mounted upon the main frame 2 while the other two 55 wheels are mounted upon auxiliary or extension frame 3. As shown to advantage

in Figure 5 the lower portion of the main frame 2 is divided into five compartments designated by the numerals 4, 5, 6, 7 and 8. Within the compartment 4 there is situated 60 the toilet outfit 9 and a bonnet box 10. A bath tub 11 is situated in the compartment 5 and a basket 12 is situated therein. Suitable thermos devices 13 are mounted in the compartments 6 and 8 while a drawer 14 65 is slidably mounted within the compartment 7. Above these compartments designated by the numerals 4 to 8 inclusive there is situated a bed which is mounted upon the floor 15. A sliding floor 16 is mounted 70 thereon having its end connected to the sliding or extension frame 3 so as to move therewith and act as an extension to the floor 15. The bed is provided with the spring device 17 which is hinged centrally at 18 so that its sections may be folded over upon each other as shown in Figures 6 and 7. The mattress 19 is also formed in two sections being hinged by the straps 20 and is extended as shown in Figure 3 and folded 75 as indicated in Figures 6 and 7. The upper portion of the vehicle is screened.

The top 22 is hinged at 23 to the main frame 2 and is provided with a section 24 which is hinged thereto at 25 and when the main section 2 and the extension section 3 are together this cover will be positioned as indicated in Figure 4 and when extended will be positioned as indicated in Figure 3. If so desired the cover may be allowed to hang 80 parallel with the side of the frame 2 as indicated by the dotted lines in Figure 9 or may be raised slightly and held so by means of the slotted rod 27 which engages the bolt 29 having a thumb nut thereon. The section 24 is held in engagement with the cover 22 by a bolt and nut 29 as indicated in Figure 9. As indicated in Figure 7 the cover consists of a rectangular frame having stretched thereover mesh wire similar to the side portions 85 of the bed compartment.

The end portions of the main frame 1 are provided with the eye bolts 30 so as to receive the rod 31 which has one end fixed at 32 to the extension frame 3. Access may be had to the compartments 4 and 6 through the doors 35 and to the compartments 6 and 8 through the doors 36. In order to provide a table I have slidably mounted on the under face of the floor 15 a platform 37 which is provided with the longitudinally extending slots 38 adjacent its side edges as shown to ad- 90 95 100 105 110

vantage in Figure 5 which slots engage the bolts 39 extending downwardly from the floor 15. This platform 40 is adapted to be moved outwardly from one end of the vehicle as shown 5 to advantage in Figure 6 and has hinged to its outer end a plurality of legs 41 which are braced by the arms 42 being pivoted at one end to the edges of the table 37 while their other ends are provided with slots 43 10 for engaging a bolt 44 whereby the legs 41 may be folded as indicated in Figure 2.

While the preferred embodiments of my invention have been described in detail, it must be understood that I do not wish to be 15 limited to the particular construction set forth, since various changes in the form, proportions, and arrangements of parts, and in the details of construction may be resorted to without departing from the spirit

and scope of the invention, or destroying any 20 of the advantages contained in the same, heretofore described and hereinafter claimed.

Having thus described my invention what I claim as new is:—

In combination, a main frame, an extensi- 25 ble frame associated therewith, a cover for the main frame, a cover section hingedly mounted on said cover and adapted to swing over the extensible frame when it is ex- tended from the main frame in the manner 30 and for the purpose specified.

In testimony whereof I affix my signature in presence of two witnesses.

MRS. ALLA B. BICKHAM.

Witnesses:

J. A. ROSCOE.
